W. E. HANCOCK,
OIL WELL ATTACHMENT.
APPLICATION FILED DEC. 8, 1920.

1,412,863.

Patented Apr. 18, 1922.

UNITED STATES PATENT OFFICE.

WILLIAM E. HANCOCK, OF TULSA, OKLAHOMA.

OIL-WELL ATTACHMENT.

1,412,863.

Specification of Letters Patent. Patented Apr. 18, 1922.

Application filed December 8, 1920. Serial No. 429,086.

To all whom it may concern:

Be it known that I, WILLIAM E. HANCOCK, a citizen of the United States of America, and resident of Tulsa, in the county of Tulsa, 5 and State of Oklahoma, have invented certain new and useful Improvements in Oil-Well Attachments, of which the following is a specification.

This invention relates to oil wells and an 10 oil well equipment and particularly to improvements in the valve and valve controlling elements employed during the pumping operation in oil wells, the said invention having for its object the provision of novel 15 means for dislodging or removing accumulations of foreign substances which might be interposed between the valve and its seat and which might permit a leakage of oil being pumped so that it would not be held 20 above the valve while the return stroke of the piston or lifting element was occurring.

A still further object of this invention is to provide a valve for the purpose indicated 25 associated with a traveling member adapted to receive an impact from the piston of the pumping elements to force the valve toward its seat and crush any sand or other foreign element which impaired the operation of the valve.

30 A still further object of this invention is to provide an attachment for a valve cage in such operative relation to the valve as to force the valve toward the seat for the purpose indicated and to so position the said 35 attachment as to be in operative relation to a reciprocating element such as the piston or sucker as to make it possible to impart the motion of the said piston or sucker to the element.

40 With the foregoing and other objects in view, the invention consists in the details of construction, and in the arrangement and combination of parts to be hereinafter more fully set forth and claimed.

45 In describing the invention in detail, reference will be had to the accompanying drawings forming part of this application wherein like characters denote corresponding parts in the several views, and in 50 which—

Figure 1 illustrates a sectional view of a working barrel and the pumping elements associated therewith;

55 Figure 2 illustrates an enlarged sectional view of the valve and means for forcing the valve to its seat;

Figure 3 illustrates a sectional view on a line corresponding with the line 3-3 of Fig. 1; and

Figure 4 illustrates a sectional view on a 60 line corresponding with the line 4-4 of Fig. 2.

In these drawings I have illustrated a working barrel 5 having a series of tubings 6 and 7 therein and couplings such as 8 and 9 by which the parts are connected together, and I have also illustrated the means for collecting sand which may be present in the oil being pumped, but as the sand arresting construction forms a part of another application of mine, a description of the details of construction of these parts will not be attempted.

The tube 6 has a collar 10 secured on it which collar has lugs 11 radiating therefrom and bearing against the inner wall of the barrel to hold the tube 6 in spaced relation to the barrel, and there is also a collar 12 of similar construction but of larger bore fitted to the tube 7. The piston 13 and its rod 14 are of ordinary construction and work in the tube 7 during the pumping operation. The valve cage 15 which, generally speaking, is of standard construction, has a coupling 16 by which it is connected 85 to the tube 6 and this coupling has a nipple 17 threaded in the valve cage and a tapered threaded bore 18 by which it is connected to the tube 6. The valve cage has the usual valve seat 19 and valve 20 which in practice, 90 as heretofore stated, sometimes becomes unseated by the interposition of foreign substances such as sand. To crush or remove the sand or material which interferes with the action of the valve, the top of the valve 95 cage is provided with a threaded aperture 21 in which a hollow bushing 22 is threaded through which a plunger 23 is slidable, the said plunger terminating in a head 24 with a recessed or concaved surface 25 adapted 100 to abut the valve and force it to its seat. The plunger has a threaded end 26 on which nuts 27 and 28 are threaded and there is a disk 29 on the threaded end of the plunger located between the two nuts, and these nuts and disk form what may be termed a head adapted to be struck by the piston, under certain conditions, during the pumping operation. The plunger is held normally projected by 105 a spring 30 which encircles the said plunger and bears against the upper end of the bushing and the nut 27 and therefore, the plun-

ger is yieldably held projected and automatically returns to its normal position shown in Fig. 2.

Ordinarily during the pumping operation 5 and when there is no impairment of action of the valve due to deposits such as has been mentioned, the stroke of the piston will terminate free of the upper end of the plunger, but as is well known, provision is made, 10 through the use of a turn buckle or such expedient, for increasing or diminishing the stroke of the piston rod and hence by lengthening the piston rod through the use of a turnbuckle, the stroke of the piston could 15 be made such as to cause it to force the plunger downwardly into engagement with the valve and after the valve has been caused to resume its normal operation, the turnbuckle could be re-adjusted for the normal stroke 20 of the piston.

It follows, therefore, from an inspection of the drawing and from the foregoing description, that the device embodying the invention may be installed in wells now in operation by substituting valve cages of this 25 type for those now in common use.

It is also shown that the hood or deflector 31 is supported on the valve cage and held thereon by a nut 32 threaded on the external 30 surface of the bushing. This hood in the present embodiment of the invention is flared toward the bottom or mouth, although it may be straight if desired.

I claim:

35 1. In a pumping mechanism, a barrel having a piston operating therein, a tube having a valve cage thereon located below the piston, a valve in the cage, a plunger in operative relation to the valve for forcing it on 40 its seat and projecting into the path of travel of the piston during an abnormal stroke of the piston, and means for normally holding the plunger elevated.

2. In an oil pumping mechanism, a barrel, 45 an oil tube therein, a valve for controlling the passage of oil through the tube, a valve cage connected to the tube in which the valve is located, a plunger slidably in the cage and adapted to abut the valve for forcing 50 it on its seat, means for holding the plunger normally elevated, and a pumping piston mounted for operation above the plunger and adapted to operate free of the plunger normally and to project into engagement with the plunger during abnormal 55 operation.

3. In an oil pumping mechanism, a tub-

ing for the passage of oil, and having a valve seat, a valve operating in conjunction with the valve seat, a plunger slidably guided in operative relation to the valve and adapted to strike the valve for forcing it on its seat, means for holding the plunger normally elevated and in the path of travel of a pumping piston, as and for the purpose 60 described.

4. In an oil well equipment, a pumping tube, a valve cage thereon, a valve in the cage, a bushing threaded in the upper end of the valve cage, a plunger slidable through 70 the said bushing and extending into the cage, means for holding the plunger normally elevated, a pumping piston operating above the plunger under normal conditions free of the said plunger, the said plunger 75 being operated upon an adjustment of the plunger for abnormal stroke, a deflector on the said cage having a flared lower end, and means for holding the deflector in the bushing and cage.

5. A structure of the character described comprising a standing valve having a valve cage, a valve element loosely mounted therein, a follower slidably carried by the cage for engaging the valve member, a fishing 85 tool engaging element carried by the follower and positioned for engagement by a piston whereby the piston may serve as means for driving the follower into positive engagement with the valve element, and 90 resilient means between the fishing tool engaging element and valve cage to yieldably retain the follower in a raised position.

6. In a structure of the character described, a standing valve having a movably 95 mounted valve element, and means for engaging the valve element and returning the same to a closed position movably mounted for engagement by a piston and yieldably retained in an inoperative position.

7. In an oil pumping mechanism, a tube for the passage of oil and having a valve seat, a valve operating in conjunction with the valve seat, a plunger movable in operative relation to the valve and adapted to strike the valve for forcing it on its seat, means for holding the plunger normally elevated, a pumping element operatively arranged above the plunger normally free of the said plunger and operative to strike the 105 plunger when moving abnormally, as and for the purpose described.

WILLIAM E. HANCOCK.
